UNITED STATES PATENT OFFICE.

CHARLES T. MEYER AND VICTOR E. MEYER, OF LYON'S FARMS, NEW JERSEY, ASSIGNORS TO EDWARD C. SAMPSON, OF NEW YORK, N. Y.

DESIGN FOR OIL-CLOTH PATTERN.

Specification forming part of Design No. 6,061, dated August 20, 1872.

To all whom it may concern:

Be it known that we, CHARLES T. MEYER and VICTOR E. MEYER, of Lyon's Farms, county of Union, State of New Jersey, have originated and designed a new Pattern for Floor Oil-Cloths, Carpets, or other fabrics, of which the following is a full, clear, and exact description, reference being had to the accompanying specimen or drawing making a part of this specification, and marked or designated as No. 786, which fully represents said design, and is sufficient, without further aid, to enable any person skilled in the art to repeat it for practical use.

The colors employed for the different portions of this design may be varied, to suit the convenience or taste of the manufacturer.

What we claim as our invention, and desire to secure by Letters Patent, is—

The design or pattern for floor oil-cloths, carpets, and other fabrics, known and described.

CHAS. T. MEYER.
VICTOR E. MEYER.
